THROTTLE FOR FREE-PISTON UNITS

Walter A. Ledwith, Hartford, Conn., assignor to
 United Aircraft Corporation, East Hartford,
 Conn., a corporation of Delaware

Application July 23, 1943, Serial No. 495,935

2 Claims. (Cl. 230—56)

1

In throttling a part of a double-acting free-piston engine-and-compressor unit in adapting it for compressing a gaseous medium of greater density, throttles are provided for closing off the intake to one end of the compressor cylinder as disclosed in the copending Kalitinsky application, Serial No. 495,918, filed July 23, 1943. In this application the compressor has a number of intake passages for the inner ends of the compressor, with a separate throttle in each passage.

A problem in throttling one end of the compressor cylinder is to close all the intake passages so that the compressor will function as a single-acting unit. A feature of this invention is to provide for interlocking the several throttles so that they will all open or close as a unit, thereby assuring a complete closing of the intake passages.

Many free-piston engines have opposed pistons for balancing the unit in which event the inner ends of the compressor cylinders must be throttled simultaneously in adapting the unit to a higher pressure or density. Another feature of the invention is the control of all of the compressor throttles simultaneously.

Other objects and advantages will be apparent from the specification and claims, and from the accompanying drawings which illustrate an embodiment of the invention.

Fig. 1 is a sectional view through the free-piston engine-and-compressor unit.

Fig. 2 is a sectional view substantially along the line 2—2 of Fig. 1.

The unit shown includes an engine cylinder 10 having reciprocating pistons 12 and 14 to which compressor pistons 16 and 18 in cylinders 20 and 22 are integrally connected. Sleeves 24 and 26 attached to the compressor pistons complete the reciprocating piston assemblies. The sleeves in combination with stationary pistons 28 and 30 form air spring cylinders.

The piston assemblies are moved apart by the burning of fuel injected into engine cylinder 10. Air compressed in the air spring cylinders on the power stroke returns the piston assemblies. The assemblies are always maintained at equal distances from the center of the engine cylinder by a linkage, which may include racks 34 extending from the compressor pistons and engaging opposite sides of a pinion 36.

Intake manifold 38 conducts air to intake valves 40 through which air alternately enters opposite ends of the compressor cylinders. The compressed air leaves the cylinders through discharge valves 42, also at opposite ends of the com-

2

pressor cylinders, and passes through scavenge manifold 44 through ports 46 and 48 which are uncovered by pistons 12 and 14 at the end of the power stroke, thereby permitting air to be blown through the engine cylinder and exhaust ports 50 and 52 into exhaust manifold 54.

When an increase in the density of a medium being pumped has shortened the strokes of the pistons, the change in density is compensated for by throttling the intake to the inner ends of the compressor cylinders. Pairs of valves 56 and 58 close the passages 60 and 62 leading from intake manifold 38 to the chamber 64 which communicates with intake valves 40 at the inner ends of the compressor cylinders. Throttling the compressor by closing valves 56 and 58 converts the unit into a single-acting compressor with the work of compressing being done in the outer ends of the compressor cylinders.

As shown in Fig. 1 the pair of valves 56 are mounted on a rod 66 journaled in lugs 68 on the compressors. Rod 66 has an extension shaft 70 extending through a support 72 in the intake manifold and having an arm 74 on the outer end, by which rod 66 with the throttles thereon may be turned.

The pair of valves 58 are mounted on a rod 78 extending parallel to rod 66 and also journaled in lugs on the compressors. Rod 78 has a projecting arm 80 connected by a link 82 to an arm 84 on extension shaft 70. In this way turning shaft 70 by arm 74 closes both pairs of valves 56 and 58 simultaneously.

It is to be understood that the invention is not limited to the specific embodiment herein illustrated and described, but may be used in other ways without departure from its spirit as defined by the following claims.

I claim:

1. A free-piston engine-and-compressor unit including an engine cylinder, opposed pistons therein, spaced compressor cylinders located at opposite ends of the engine cylinder, and a piston in each compressor cylinder connected to and moving with the adjacent engine piston, in combination with a supporting structure interconnecting said compressor and engine cylinders and having passages for admitting fluid to one end of each compressor cylinder, and means for throttling the flow of fluid through said passages to said one end of each compressor, said means including throttles in each of said passages, a pair of rods mounted for turning in the unit, each rod having mounted thereon at least two of the throttles, a connection between the rods to cause the

rods to turn simultaneously and one of said rods extending outside of the unit to provide for turning the rods.

2. A free-piston engine-and-compressor unit including an engine cylinder, opposed pistons therein, spaced compressor cylinders located at opposite ends of the engine cylinder, and a piston in each compressor cylinder connected to and moving with the adjacent engine piston, in combination with a supporting structure interconnecting said compressor and engine cylinders and having passages for admitting fluid to one end of each compressor cylinder, and means for throttling the flow of fluid through said passages to said one end of each compressor, said means including throttles in each of said passages, each throttle being substantially in the form of a disc adapted to fit within and close a substantially cylindrical portion of the associated passage, a pair of rods on which said throttles are mounted, each rod supporting at least a pair of throttles, a connection between the rods to cause them to turn simultaneously and one of said rods projecting outside of the unit to provide for turning the rods for adjusting the position of the throttles.
